Felix Gilbert, New York, N.Y., assignor to General
Alarm Corporation, New York, N.Y., a corpora-
tion of Delaware

Filed Nov. 23, 1966, Ser. No. 4,795

Term of patent 14 years

(Cl. D50—5)

FIG. 1 is an elevational view of a combination chain lock and alarm for doors embodying my design;

FIG. 2 is a top plan view of the design illustrated in FIG. 1;

FIG. 3 is an elevational view taken from the left side of FIG. 1, as viewed;

FIG. 4 is an elevational view taken from the right side of FIG. 1, as viewed, and illustrates the right hand element of FIG. 1; and

FIG. 5 is a cross sectional view taken along the lines 5—5 of FIG. 1.

The chain in FIGS. 3 and 4 is shown broken away for convenience of illustration.

I claim:

The ornamental design for a combination chain lock and alarm for doors, as shown and described.
